Inventor

Luta L. Conrad,

By Clarence A. O'Brien.
Attorney

Patented June 16, 1925.

UNITED STATES PATENT OFFICE.

LULA L. CONRAD, OF JOHNSTOWN, PENNSYLVANIA.

ELECTRIC IRON.

Application filed June 30, 1924. Serial No. 723,269.

To all whom it may concern:

Be it known that I, LULA L. CONRAD, a citizen of the United States, residing at Johnstown, in the county of Cambria and State of Pennsylvania, have invented certain new and useful Improvements in Electric Irons, of which the following is a specification.

This invention relates to an electric iron, and is more particularly adapted to a switch for controlling the opening and closing of the circuit to the heating coils in the iron.

One of the important objects of the present invention is to provide a switch of the above mentioned character, which is so mounted as to render the same accessible while the iron is in use, thus enabling a person to readily cut off the current to the iron instantaneously, whenever desired.

A further object of the invention is to provide an electric switch for electric irons, which is so mounted as to not interfere with the handling of the iron, the switch being preferably mounted in the handle.

A further object of the invention is to provide a device of the above mentioned character, which is simple in construction, inexpensive, strong and durable, and further well adapted for the purposes for which it is designated.

Other objects and advantages of the invention will become apparent during the following description.

In the accompanying drawing, forming a part of the specification and in which like numerals designate like parts throughout the same:

Figure 1 is a view of an electric iron, partly in side elevation and partly in section, showing my invention in position thereon; and

Figure 2 is an enlarged fragmentary sectional view of the portion of the handle with the switch mounted in position therein.

In the drawing wherein for the purpose of illustration is shown the preferred embodiment of my invention, the numeral 1 designates generally an electric iron of any well known construction, and the same comprises the base 2. Mounted on the base 2 is the handle supporting frame designated generally by the numeral 3, and on the upper end thereof is supported the usual handle 4, which is constructed of any suitable non-conducting material, such as hard rub-

ber, fiber or the like. The heating element located in the base 2 of the iron 1, is designated generally by the numeral 5, and one of the terminals which is associated with the heating coil is designated at 6. The contact 7 is provided and is adapted to be connected to the usual cord plug, in the manner well known in the art. The handle 4 is provided with a longitudinally extending central bore 8, and the same terminates at its forward end in the enlarged pocket or recess 9, which provides a means for supporting in the forward end of the handle 4, the electric socket 10, which may be of any conventional construction and is preferably of the push button type, the push buttons being illustrated at 11 and 12 respectively in the drawings.

The upper portion of the forward end of the handle is cut away to enable the switch member 10 to be inserted in the recess 9, and a cover or cap 13 is provided for closing the open portion of the handle after the switch has been inserted in the opening 9. The rear end of the handle is cut away and provides a means for receiving the upper portion of the conduit 14 which extends from the handle and to the base 2 of the electric iron. The conduit furthermore communicates with the bore 8 in the handle 4 and the opening 15 is provided in the base of the iron in the manner as clearly illustrated in Figure 1 of the drawings.

A wire 16 extends from a terminal or contact 6 through the conduit or is connected to one of the contacts in the switch 10, while the other wire 17 is attached to the cord terminal or contact 7 and also extends through the conduit and bore and is connected to the other contact in the switch. The support for the plug associated with the cord is illustrated at 18 in the drawing, the same extending from the conduit 14 at a point in close proximity to the terminal or contact 7.

The provision of a switch in the handle of an electric iron, in the manner as above set forth enables the person using the iron to instantly control the current to the heating coil in the base of the iron and the convenient arrangement of the switch enables the use of the iron without interfering with the switch, yet rendering the same accessible at all times whenever it is necessary to cut off the current to the heating coils or units in the base of the iron.

In combining the handle with the switch for opening and closing the circuit to the heating coil in the iron, considerable time will be saved, while saving a considerable amount of current in the use of the iron.

A device of the character above described may be made at a very low cost and will further be strong and durable and the parts are further so arranged as to enable the 10 same to be readily disassembled, whenever necessary.

While I have shown the preferred embodiment of my invention, it is to be understood that various changes in the shape, size 15 and arrangement of parts, may be resorted to, without departing from the spirit of the invention and the scope of the appended claim.

Having thus described my invention, what I claim is:

An electric iron including a base, a heating element in said base, a handle positioned above the base a substantially U-shaped supporting frame having its bight portion detachably connected to the top of said base 25 and having the upper ends of its arms fastened to and supporting said handle, a conduit depending from one end of said handle, and communicating with a recess formed in said base, one end of said handle 30 being recessed to provide a pocket, for reception of a controlling switch, and a removable cover for said pocket.

In testimony whereof I affix my signature.

Mrs. LULA L. CONRAD.
